UNITED STATES PATENT OFFICE.

WALTER V. TURNER, OF WILKINSBURG, PENNSYLVANIA, ASSIGNOR TO THE WESTINGHOUSE AIR BRAKE COMPANY, OF PITTSBURGH, PENNSYLVANIA; A CORPORATION OF PENNSYLVANIA.

FLUID-PRESSURE BRAKE.

1,109,714.

Specification of Letters Patent.

Patented Sept. 8, 1914.

Application filed February 6, 1905. Serial No. 244,265

To all whom it may concern:

Be it known that I, WALTER V. TURNER, a citizen of the United States, residing in Wilkinsburg, in the county of Allegheny 5 and State of Pennsylvania, have invented a certain new and useful Improvement in Fluid-Pressure Brakes, of which improvement the following is a specification.

This invention relates to automatic fluid 10 pressure brake systems, and has for one of its objects to provide an improved distributing valve device adapted to be applied to locomotives or cars for controlling the supply of air to and its release from the brake 15 cylinder.

Another object is to provide an improved 20 form of engineer's brake valve having ports coöperating with the improved distributing valve device, whereby the locomotive brakes 25 may be applied and released, if desired, without applying the train brakes, and also adapted to hold the locomotive or driver 30 brakes applied while releasing the automatic train brakes.

A further object of this invention is to 35 provide an improved combined automatic and straight air brake equipment for locomotives whereby the driver brakes may be controlled by straight air independently of 40 the automatic train brakes.

This distributing valve device is an improvement on that covered by Patent No. 898,885 of H. T. Herr, dated September 15, 1908.

I will now describe more particularly one 45 form of apparatus embodying the various features of my improvements, reference being had to the accompanying drawings, in which—

Figure 1 is a diagrammatic view of the 50 locomotive equipment, the engineer's brake valve being indicated in plan with top removed showing ports in the rotary valve seat, and the parts of the distributing valve 55 device being shown in section; Fig. 2 a face view of the rotary valve; Fig. 3 a diagram showing the relative position of the ports in the rotary valve and its seat in the full release position of the engineer's brake valve, 60 the ports in the seat being indicated in light lines and the ports in the valve in heavy lines; Fig. 4 a similar diagram showing position of ports in running position; Figs. 5 and 6 similar diagrams illustrating service 65 and lap positions respectively; Figs. 7 and

8 similar diagrams showing positions for straight air application and straight air lap respectively; Fig. 9 a diagrammatic view of a locomotive equipment similar to Fig. 1 but showing a modification including a separate straight air brake valve; Fig. 10 a face view of the small straight air valve; Fig. 11 a diagrammatic view of a brake equipment embodying certain features of my invention, and particularly adapted for cars, a part of 60 the distributing valve device being shown in section; Fig. 12 a plan of the slide valve seat; and Fig. 13 a face view of the slide valve of the triple valve portion of the distributing valve device shown in Fig. 11. 70

According to the construction shown in Fig. 1, my improved distributing valve device is illustrated as comprising three separate parts, the triple valve portion 1, the regulating and release valve mechanism 2, 75 and the main supply valve 3. The main reservoir 4 is connected by means of main reservoir pipe 5 with the supply valve 3 and also with the engineer's brake valve 6, while the train pipe 7 communicates with the piston chamber 25 of the triple valve device 1. The piston 26 is connected by stem 29 with the slide valve 30 in the valve chamber 27, which communicates through pipe 40 with the auxiliary chamber 41. In the slide valve 80 seat are located ports 31 and 32, the former leading by pipe 39 to the regulating chamber 42, and the latter normally communicating with pipe 38 leading to a port 14 in the seat of the engineer's brake valve. The cavity 28 in slide valve 30 is adapted to connect the two ports when the valve is in release position, as indicated. Any desirable means may be employed for charging the auxiliary chamber 41, but according to the 85 preferred construction a port 33 is provided in the slide valve seat and communicates by a pipe 50 with the main reservoir, said port 33 being so located at one side as to be covered by a slight outward movement of the slide valve 30 when the pressure in the auxiliary chamber rises to or slightly exceeds that of the train pipe. The regulating and release valve mechanism comprises a movable abutment, or piston 45, subject to 90 the pressure of the regulating chamber 42 on one side and on the other side to the valve chamber 44, which is in open communication with the brake cylinders through pipe 58. The stem 46 of piston 45 operates the valve 95 100 105 110

47 for controlling the brake cylinder release port 48, and is also adapted upon forward movement to engage the stem of the small regulating valve 49 and open the same for 5 venting air from the chamber 51 back of piston 52 of the supply valve device 3 through connecting pipe or passage 61 to the brake cylinder. The stem 55 of piston 52 operates the slide valve 56 for controlling 10 the port 57 communicating with pipe 58 leading to any number of brake cylinders, 59. A safety valve 60 may be provided for the brake cylinders, if desired. Main reservoir pressure is admitted from pipe 5 to the 15 valve chamber 54, and leaking around the piston 52 will readily equalize in chamber 51 when the small regulating valve 49 is closed, whereupon the spring 53 holds the slide valve in position with supply ports 57 20 closed. While this form of supply valve device is considered preferable, it will be evident that any valve mechanism operated by the regulating piston 45 for controlling the supply of air to the brake cylinder and 25 its release therefrom, may be employed.

In the seat of the rotary valve of the engineer's brake valve are located the usual train line port 8 communicating with train pipe 7, exhaust port 10 leading to the atmosphere, cavity 9, preliminary discharge port 30 12, feed port 11, and equalizing port 13, all of which may be of the usual construction. In addition to these ports I provide a port 14 communicating with pipe 38 for controlling pressure in the regulating chamber, as hereinafter more fully explained. The rotary valve 15 has the usual through port 16 and large cavity 17 provided with openings 18, 19, 23 and 24 in the face of the valve, 35 through ports 20 and 21, and small cavity or groove 22.

With the engineer's brake valve in its normal running position, as indicated in Fig. 4, air from the main reservoir which enters the 45 brake valve through pipe 5 flows through port 20, feed port 11 and the feed valve device 62 to the train pipe in the usual manner, charging the same to the normal standard degree of pressure. As the pressure 50 rises in chamber 25 on the triple valve piston 26, the slide valve 30 is moved to its inner position, in which the port 33 is open, thereby charging the auxiliary chamber 41 and the valve chamber 27 from the main reservoir through pipe 50 at substantially the 55 same rate that the train pipe is charged. When the system is fully charged the pressure in valve chamber 27 acting on piston 26 moves the slide valve sufficiently to cover 60 port 33 and cut off further increase in the pressure of the auxiliary chamber. In this running position of the engineer's brake valve the extension 63 of cavity 22 establishes communication from the port 14 and 65 pipe 38 to the exhaust port 10, so that the

regulating chamber is in open communication with the atmosphere and the brakes are released. When the engineer's brake valve is turned to position for service application, indicated in Fig. 5, the regulating chamber 70 port 14 and feed port 11 are closed and the preliminary discharge port 12 is opened to the exhaust port 10 through the groove or cavity 22, thereby making a reduction in the equalizing reservoir and in the train pipe 75 in the usual way, the brake valve being turned to lap position, Fig. 6, in which all ports are closed, when the desired reduction is made. The reduction in train pipe pressure operates to apply the automatic train 80 brakes in the usual manner, and also acts upon the triple piston 26 of my improved distributing valve device, causing the same to move out against the spring pressed graduating stem 43 and open the port 31, whereupon air under pressure from the auxiliary chamber flows to the regulating chamber 42 charging the same to the desired degree of 85 brake cylinder pressure. As the pressure in the auxiliary chamber falls to equal that of the train pipe the graduating spring moves the piston 26 and valve 30 to lap and closes the service port 31. The pressure in the regulating chamber actuates the piston 45 to move valve 47 to close the exhaust ports 48, 90 and to open the small regulating valve 49, thereby releasing air from the chamber 51 in the rear of piston 52 of the supply valve to the brake cylinder space, so that the main reservoir pressure in valve chamber 54 on the opposite side instantly actuates the piston to move the slide valve 56 to open the port 57 and supply air from the main reservoir through the pipe 58 to the brake cylinders and the chamber 44. As soon as this pressure equals or slightly exceeds that of the regulating chamber on the opposite side of piston 45 the same will be moved back 95 sufficiently to permit the small regulating valve 49 to close but not to open the exhaust ports 48. The instant the regulating valve closes the pressure equalizes upon opposite sides of the supply piston 52 and the spring 53 moves the piston and valve to close the 100 brake cylinder supply port 57. In a similar manner, a further reduction operates to increase the brake cylinder pressure, which always corresponds to that of the regulating chamber 42. Should there be any leakage 105 from the brake cylinders the pressure of the regulating chamber operating upon piston 45 causes the same to slightly open the regulating valve 49, whereupon the supply valve 56 opens sufficiently to supply air to the 110 brake cylinder to compensate for such leakage, so that the brake cylinder pressure is maintained substantially constant and equal 115 to that in the regulating chamber. To release the automatic train brakes the engineer's brake valve is turned to full release 120 125 130

- position, indicated in Fig. 3, whereupon air from the main reservoir flows through ports 16, 9, large cavity 17 and port 8 to the train pipe 7, increasing the pressure therein and causing the release of the triple valves in the usual way. The pressure is also increased in the chamber 25 on piston 26, and moves the slide valve 30 to release position, as shown in Fig. 1, but as port 14 of pipe 38 is closed 10 at the seat of the rotary valve of the brake valve the air cannot escape from the regulating chamber, consequently the engine brakes will be held applied as long as the engineer's brake valve remains in full release position.
- 15 When the brake valve is returned to running position, the compressed air in the regulating chamber escapes to the atmosphere through ports 31, 32, pipe 38, port 14, cavity 63, and exhaust port 10 in the brake valve, so that the brake cylinder pressure in chamber 44 immediately moves the piston 45 and valve 47 to open the exhaust port, or ports, 48, and release the brake cylinders, 59. By means of thus controlling the port 14 at the 20 brake valve the engine brakes will be held applied temporarily while the train brakes are being released, thereby bunching the train and preventing the surging ahead of the locomotive and forward cars upon release of the brakes, which, with the apparatus now in use, often results in shocks and strains, sometimes causing a break-in-two of the train.
- If it is desired that the distributing valve 25 device operate to release the engine brake cylinders at the same time that the train brakes are released, the exhaust port 32 may be open to the atmosphere, and for this purpose I have provided a cock 36, having 30 ports 35 and 37, adapted in one position to connect pipe 38 with port 32 and pipe 39 of the regulating chamber, and when turned to another position to cut off communication from pipe 38 to pipe 39 and to 35 connect port 32 with the atmosphere through exhaust port 34. In the case of double heading, or where two or more locomotives are coupled up for drawing a train, the cocks 36 upon the second or following 40 locomotive will be turned to this latter position, so that the distributing valve devices on such locomotives will be operated only in accordance with the usual variations in train pipe pressure, while on the first locomotive, or in case there is only one locomotive, the cock 36 is set in the first position, as shown in Fig. 1, in which communication is taken from the pipe 38 to the pipe 39 and the port 32. With the cock 36 set in the second 45 position on the second locomotive, the brakes may be graduated off with the train brakes when the train pipe pressure is slightly increased, as this increase in train pipe pressure is sufficient to move the piston 26 and slide valve 30 to release position, opening the exhaust port 32 and uncovering port 33 leading to the reservoir 4. Air from said reservoir then flows into the valve chamber 27 and acting on the piston 26 moves the slide valve 30 back to lap position. In the meantime, a portion of the air in the regulating chamber has escaped to the atmosphere, causing a reduction therein, whereupon the regulating and release valve device 2 operates to diminish the brake cylinder pressure. With this arrangement the engine brakes may be controlled to a certain extent independently of the train brakes, as will now be explained. The port 21 is so located in the rotary valve 15 of the engineer's brake valve that when turned to straight air application position, as indicated in Fig. 7, this port registers with port 14, and air from the main reservoir flows through pipe 38, ports 35 and 37 in cock 36, to pipe 39 and the regulating chamber 42, charging the same to any desired degree of pressure, after which the rotary valve is turned to straight air lap position, indicated in Fig. 8. The piston 45 then operates as before described to close exhaust ports 48 and open the regulating valve 49, thereby causing the operation of main valve 56 to supply the same degree of pressure to the brake cylinders as obtains in the regulating chamber. By turning the rotary valve to running position, and then back to straight air lap, the pressure in the regulating chamber may be reduced by any desired amount, whereupon the brake cylinder pressure in chamber 44 acting on the opposite side of piston 45 operates to open exhaust port 48 and release a portion of the air from the brake cylinder until the pressure equals or is slightly less than that remaining in the regulating chamber, whereupon the exhaust port is closed. To entirely release the engine brakes the rotary valve is left in running position, Fig. 4. If, after the automatic brake is applied, it is desired to release the train brakes and hold the engine brakes on, this may be done by moving the engineer's brake valve to full release position, Fig. 3, and then to straight air lap position, Fig. 8, thereby increasing the train pipe pressure in the usual manner but holding the regulating chamber closed, after which the engine brake may be graded down or released at any time, as desired, as above described. It will now be apparent that by means of this feature of my improvement the locomotive brakes may be applied and released, or graded up or down at will, entirely independently of the train brakes.
- It will be noticed that in the "running" and both straight air positions, the ports 29 and 23, which may be either elongated or made in the form of a plurality of holes, are in register with the feed port 11 and equalizing port 13 respectively, so that air

is supplied through the feed valve to the train pipe and equalizing reservoir, maintaining the same at the desired degree of pressure while the engine brakes are being controlled with straight air.

The straight air feature may be embodied in a straight air brake valve separate from the engineer's brake valve, if desired, as indicated in Fig. 9, in which case the pipe 38 10 is connected to port 64 in the seat of straight air brake valve 65, which is provided with a small rotary valve 66 having a port 64 with exhaust port 69 leading to the atmosphere, the chamber above the rotary valve being 15 connected with the main reservoir pipe 5 in the usual way. With this construction the engine brakes may be applied independently of the train brakes by turning the straight air brake valve to application position, in 20 which port 67 registers with port 64 and air is supplied through pipe 38 to the regulating chamber, which operates to supply air to the engine brake cylinders as before described. The pressure of the regulating 25 chamber may then be released or graded down as desired by turning valve 66 so that cavity 68 connects port 64 and exhaust port 69. The normal position of the valve 66 is an intermediate one, in which the port 64 is 30 closed so that pressure may accumulate in the regulating chamber when the automatic brakes are applied with the engineer's brake valve 6 or by a reduction in train pipe pressure. Another important advantage derived 35 from the use of the separate straight air brake valve is that after the engine and train brakes have been applied in the usual manner with the automatic system and the engineer's brake valve is on lap, the engine 40 brakes may be released without releasing the train brakes by merely turning the straight air valve 66 to release position, in which the air from the regulating chamber exhausts to the atmosphere through pipe 38, ports 64, 45 68 and 69. The engine brakes may afterward be applied with straight air and the automatic train brakes may then be released for recharging while the engine brakes are held applied, thereby giving a complete and 50 independent control of the engine and train brakes.

The modification shown in Fig. 11 illustrates my improved distributing valve device adapted for application to cars or other 55 vehicles not provided with an air compressor or independent source of air pressure, and in this case I employ a large auxiliary storage reservoir, 70, which may be charged from the train pipe 7, or in any other desirable 60 manner. According to a preferred construction, a check valve 71 is interposed between the train pipe and a port 72 in the seat of the triple valve device 1, while another port 73 communicates with pipe 5^a and with 65 storage reservoir 70. These ports are ar-

ranged to be uncovered by the slide valve 30 when the same is in release position, so that the auxiliary chamber 41, valve chamber 27 and storage reservoir 70 are then in open communication and are all charged 70 with air from the train pipe. When an application of the brakes is made by the usual reduction in train pipe pressure the piston 26 moves out against the graduating spring stop 43 and opens service port 31, charging the regulating chamber 42 from the auxiliary chamber 41 as before described, the ports 72 and 73 being closed by the slide valve 30 in its service position. The regulating and supply valve devices, 2 and 3, then operate to supply air from pipe 5^a and the storage reservoir 70 to the brake cylinder 59, charging the same to a degree of pressure equal to that of the regulating chamber. When the air pressure of the auxiliary chamber 41 diminishes to that of the train pipe the triple valve device moves to lap position, closing port 31 as before described. The auxiliary chamber and regulating chamber are made of such relative capacities as to give the desired degree of brake cylinder pressure corresponding to the usual reductions in train pipe pressure, but the storage reservoir may be of much larger capacity than the ordinary auxiliary reservoir, so that a number of full service applications may be made successively, if desired, without materially recharging the storage reservoir. As the pressure remaining in the storage reservoir is 95 then ordinarily much higher than that of the train pipe and auxiliary chamber at the time of releasing the brakes, a graduated release may be made, if desired, by slightly increasing the train pipe pressure and then 100 moving the engineer's brake valve to lap position. This increase is sufficient to move the triple valve piston 26 and slide valve 30 to release position, opening the exhaust port 32 and uncovering the port 73 leading to the storage reservoir. Air from the reservoir 70 then flows into the valve chamber 27 and acting on piston 26 moves the slide valve 30 back to lap position. In the meantime, a portion of the air in the regulating 105 chamber has escaped to the atmosphere, causing a reduction therein, whereupon the regulating and release valve device 2 operates as before described to diminish the brake cylinder pressure a corresponding 110 amount. In this manner the brake cylinder pressure may be graded down to any desired point or released altogether at any time. 115

While for the purposes of illustration I have shown the component parts of the distributing valve device separated, it will be evident that in actual practice these valve devices may all be combined in a single integral casing with the auxiliary chamber and the regulating chamber, thus making a 120 125 130

very compact design of apparatus, which may be secured in any convenient position on a locomotive or car.

Having now described my invention, what I claim as new and desire to secure by Letters Patent is:—

1. In a fluid pressure brake, a distributing valve device comprising a main valve for controlling the supply of fluid under pressure to the brake cylinder, a regulating chamber, a movable abutment subject to pressure of the regulating chamber and operated by an increase in pressure therein for opening the supply valve and adapted to close said supply valve when the brake cylinder pressure substantially equals the regulating chamber pressure, a release valve operated by said abutment, and means for charging and releasing fluid from the regulating chamber.

2. A distributing valve device comprising a brake cylinder supply valve, a regulating chamber, a movable abutment subject to the opposing pressures of the regulating chamber and the brake cylinder for controlling the supply valve and adapted to close said supply valve when the brake cylinder pressure substantially equals the pressure in the regulating chamber, a release valve operated by said abutment, and means for charging the regulating chamber to the desired brake cylinder pressure.

3. A distributing valve device comprising a regulating chamber, a valve mechanism operated by the opposing pressures of the regulating chamber and the brake cylinder for controlling the supply of air to and its release from the brake cylinder, and a triple valve device operated by variations in train pipe pressure for supplying air to said regulating chamber.

4. A distributing valve device comprising a regulating chamber and an auxiliary chamber, valve mechanism governed by the pressure of the regulating chamber for controlling the supply of air to and its release from the brake cylinder, and a triple valve device operated by variations in train pipe pressure for controlling the supply of air from the auxiliary chamber to the regulating chamber.

5. In a fluid pressure brake, the combination of a reservoir or source of pressure, a regulating chamber and an auxiliary chamber, valve mechanism governed by the pressure of the regulating chamber for controlling the supply of air from the reservoir to the brake cylinder, and a triple valve device operated by variations in train pipe pressure for controlling the supply of air from the auxiliary chamber to the regulating chamber, and from the reservoir to the auxiliary chamber.

6. In a fluid pressure brake, the combination of a reservoir or source of pressure, a

regulating chamber and an auxiliary chamber, valve mechanism governed by the pressure of the regulating chamber for controlling the supply of air from the reservoir to the brake cylinder, a valve controlling ports from the auxiliary chamber to the regulating chamber, and from the reservoir to the auxiliary chamber, and a piston subject to the opposing pressures of the train pipe and the auxiliary chamber for operating said valve.

7. In a fluid pressure brake, the combination with a reservoir and an automatic train pipe, of a regulating chamber, the pressure in which is controlled according to variations in train pipe pressure, valve mechanism governed by the pressure in the regulating chamber for controlling the supply of air from the reservoir to the brake cylinder and the release from the brake cylinder, and a brake valve having ports for also controlling the pressure of the regulating chamber.

8. In a fluid pressure brake, the combination with a reservoir and train pipe of a regulating chamber, valve mechanism governed by the pressure in the regulating chamber for controlling the supply of air from the reservoir to the brake cylinder, a triple valve device operated by variations in train pipe pressure for controlling the supply of air to said regulating chamber, and a brake valve having ports for also controlling the supply of air to said regulating chamber.

9. In a fluid pressure brake, the combination with a reservoir and train pipe, of a regulating chamber, valve mechanism governed by the pressure in the regulating chamber for controlling the supply of air from the reservoir to the brake cylinder and the release from the brake cylinder, a triple valve device operated by variations in train pipe pressure for controlling the supply of air to the regulating chamber, and a brake valve having ports for supplying air to and releasing the same from said regulating chamber.

10. In a fluid pressure brake, the combination with a reservoir and train pipe, of a regulating chamber, valve mechanism governed by the pressure in the regulating chamber for controlling the supply of air from the reservoir to the brake cylinder and the release from the brake cylinder, and an engineer's brake valve having a train pipe port and a port leading to the regulating chamber, and adapted in one position to open communication from the reservoir to the train pipe and hold the regulating chamber port closed.

11. In a fluid pressure brake, the combination with a reservoir, an automatic train pipe, and brake cylinder, of a regulating chamber, the release of pressure from which

- is controlled by variations in train pipe pressure, a valve for controlling the release from the brake cylinder, a movable abutment subject to the opposing pressures of the regulating chamber and the brake cylinder for operating said valve, and a brake valve having ports for also controlling the release from said regulating chamber.
12. In a fluid pressure brake, the combination with a reservoir, train pipe, and brake cylinder, of a regulating chamber, a valve for controlling the release from the brake cylinder, a movable abutment subject to the opposing pressures of the regulating chamber and the brake cylinder for operating said valve, a triple valve device operated by variations in train pipe pressure for supplying air to the regulating chamber, and an engineer's brake valve having ports for supplying air to the train pipe and for controlling the release of air from the regulating chamber.
13. In a fluid pressure brake, the combination with a reservoir and train pipe, of a regulating chamber, valve mechanism governed by the pressure in the regulating chamber for controlling the supply of air from the reservoir to the brake cylinder, and an engineer's brake valve having ports adapted in one position to supply air from the reservoir to the train pipe, and to open communication from the reservoir to the regulating chamber.
14. In a fluid pressure brake, the combination with a reservoir and train pipe, of a regulating chamber, valve mechanism governed by the pressure in the regulating chamber for controlling the supply of air from the reservoir to the brake cylinder, a triple valve device operated by variations in train pipe pressure for controlling the supply and release of air to and from the regulating chamber, a brake valve having a port normally connected to the triple valve exhaust, and a cock for opening said exhaust to the atmosphere.
15. In a fluid pressure brake, the combination with a reservoir and train pipe, of a regulating chamber, valve mechanism governed by the pressure in the regulating chamber for controlling the supply of air from the reservoir to the brake cylinder, a triple valve device operated by variations in train pipe pressure for controlling the supply and release of air to and from the regulating chamber, a brake valve having a port normally connected to the triple valve exhaust and to said regulating chamber, and a cock for closing the connection from the brake valve to the regulating chamber and opening the exhaust port to the atmosphere.
16. In a fluid pressure brake, the combination with a train pipe, of a chamber, a valve mechanism operated by varying the pressure in said chamber for controlling the release of air from the brake cylinder, and an automatic valve device operated by a gradual increase in train pipe pressure for varying the pressure in said chamber to thereby effect a partial release of the brakes.
17. In a fluid pressure brake, the combination with a train pipe, of a chamber, a valve mechanism operated by a reduction in pressure in said chamber for releasing air from the brake cylinder, and an automatic valve device operated by a gradual increase in train pipe pressure for reducing the pressure in said chamber to thereby effect a partial release of air from the brake cylinder.
18. In a fluid pressure brake, the combination with a train pipe, brake cylinder, and a source of fluid pressure, of a regulating chamber, a valve mechanism operating upon a reduction in pressure in said chamber for releasing air from the brake cylinder, and an automatic valve device comprising a movable abutment subject to the opposing pressures of the train pipe and a pressure chamber, and valve means operated by said abutment upon a gradual increase in train pipe pressure for releasing air from said chamber and for supplying air from said source of fluid pressure to the pressure chamber side of said abutment.
19. In a fluid pressure brake, the combination with a train pipe, brake cylinder, and a source of fluid pressure, of a regulating chamber, a valve mechanism subject to the opposing pressures of the brake cylinder and said chamber for controlling the release of air from the brake cylinder, an automatic valve device subject to the opposing pressures of the train pipe and a pressure chamber and operating upon a gradual increase in train pipe pressure for releasing fluid from said regulating chamber and for supplying fluid from said source of pressure to the pressure chamber side of said abutment to thereby effect a gradual release of air from the brake cylinder.
20. In a fluid pressure brake, the combination of a brake cylinder, a regulating chamber, a valve for controlling the release from the brake cylinder, and a movable abutment subject to the opposing pressures of the regulating chamber and the brake cylinder, and operated by a reduction in pressure in the regulating chamber for actuating said valve, said abutment being constantly subject on the full area of one side to the brake cylinder pressure.
21. In a fluid pressure brake, the combination of a brake cylinder, a regulating chamber, and a valve device including a movable abutment having its full area constantly subject to the brake cylinder pressure and operated by graduated reductions of pressure in the regulating chamber for graduating the release from the brake cylinder.
22. In a fluid pressure brake, the combination with a train pipe, of a chamber, a valve mechanism operated by varying the pressure in said chamber for controlling the release of air from the brake cylinder, and an automatic valve device operated by a gradual increase in train pipe pressure for varying the pressure in said chamber to thereby effect a partial release of the brakes.

tion of a brake cylinder, a regulating chamber, a valve for controlling the supply of fluid to the brake cylinder, a movable abutment having the full area subject at all 5 times to the opposing pressures of the regulating chamber and the brake cylinder and operating upon an increase in pressure in the regulating chamber for actuating said valve, and another valve operated by said 10 abutment upon a reduction in pressure in the regulating chamber for controlling the release from the brake cylinder.

23. In a fluid pressure brake, the combination of a triple valve device operated by variations in train pipe pressure for controlling the application and release of brakes, and a brake valve having means controlling the triple valve exhaust, ports and connections for controlling the train pipe pressure 20 and for effecting an application of brakes independently of the triple valve.

24. In a fluid pressure brake, the combination of a triple valve device operated by variations in train pipe pressure for controlling the application and release of brakes, and a brake valve having means controlling the triple valve exhaust, ports and connec- 25

tions for controlling the train pipe pressure, and for effecting an application of brakes independently of the triple valve, 30 and a cock for cutting off communication from the triple valve exhaust to the brake valve and opening the same to the atmosphere.

25. In a fluid pressure brake, the combination with a brake cylinder, of a regulating chamber, a movable abutment subject to the opposing pressures of the regulating chamber and the brake cylinder, and valve means controlled by said abutment for effecting the 35 supply of fluid to the brake cylinder upon an increase in pressure in the regulating chamber and for effecting the release of fluid from the brake cylinder upon a reduction in pressure in the regulating chamber, 40 said abutment having a lap position in which the application and release ports are closed.

In testimony whereof I have hereunto set my hand.

WALTER V. TURNER.
